BY *Marie Mayo*.
ATTY'S.

UNITED STATES PATENT OFFICE.

BENJAMIN F. MAYO, OF SALEM, MASSACHUSETTS, ASSIGNOR TO JAMES W. BROOKS, OF PETERSHAM, AND JOHN BROOKS, OF CAMBRIDGE, MASSACHUSETTS, TRUSTEES.

DESIGN FOR A SLUG-NAIL.

SPECIFICATION forming part of Design No. 30,112, dated January 31, 1899.

Application filed January 5, 1899. Serial No. 701,265. Term of patent 14 years.

To all whom it may concern:

Be it known that I, BENJAMIN F. MAYO, a citizen of the United States, residing at Salem, in the county of Essex and Commonwealth of Massachusetts, have invented and produced a new and original Design for a Slug-Nail, of which the following is a specification.

Figure 1 is an end view of a slug-nail, illustrating my design; and Fig. 2 is an elevation thereof viewed from the opening of the wings.

The leading feature of my design for a slug-nail consists of an elongated body transversely bent to form concavo-convex wings, the oppositely-curved surface of the wings gradually merging one into another at the transverse bend.

The slug-nail comprises an elongated body bent transversely at *b* between its ends *a'* to

form wings, said wings being concavo-convex in shape, with the oppositely-curved surfaces of the body and wings gradually merging one into the other at the point where the body is bent transversely.

Having fully described my design, what I claim, and desire to secure by Letters Patent, is—

The design for a slug-nail, substantially as herein shown and described.

In testimony whereof I have signed my name to this specification in the presence of two subscribing witnesses.

BENJAMIN F. MAYO.

Witnesses:

GEO. W. GREGORY,
EMMA J. BENNETT.
